(57) **CLAIM**

The ornamental design for a display screen or portion thereof with animated graphical user interface, as shown and described.

DESCRIPTION

FIG. 1 is a front view of showing a first image in a sequence of both a first embodiment and a second embodiment according to the claimed design;

FIG. 2 is a front view of a second image in the sequence of the first embodiment;

FIG. 3 is a front view of a third image in the sequence of the first embodiment;

FIG. 4 is a front view of a second image in the sequence of the second embodiment;

FIG. 5 is a front view of a third image in the sequence of the second embodiment;

FIG. 6 is a front view of showing a first image in a sequence of both a third embodiment and a fourth embodiment according to the claimed design;

FIG. 7 is a front view of a second image in the sequence of the third embodiment;

FIG. 8 is a front view of a third image in the sequence of the fourth embodiment;

FIG. 9 is a front view of a second image in the sequence of the fourth embodiment;

FIG. 10 is a front view of a third image in the sequence of the fourth embodiment;

FIG. 11 is a front view of showing a first image in a sequence of both a fifth embodiment and a sixth embodiment according to the claimed design;

FIG. 12 is a front view of a second image in the sequence of the fifth embodiment;

FIG. 13 is a front view of a third image in the sequence of the fifth embodiment;

FIG. 14 is a front view of a second image in the sequence of the sixth embodiment;

FIG. 15 is a front view of a third image in the sequence of the sixth embodiment;

FIG. 16 is a front view of showing a first image in a sequence of both a seventh embodiment and an eighth embodiment according to the claimed design;

FIG. 17 is a front view of a second image in the sequence of the seventh embodiment;

FIG. 18 is a front view of a third image in the sequence of the seventh embodiment;

FIG. 19 is a front view of a second image in the sequence of the eighth embodiment; and,

FIG. 20 is a front view of a third image in the sequence of the eighth embodiment.

The appearance of the transition is sequential among the embodiments as follows:

From FIG. 1 to FIG. 2 to FIG. 3 in the first embodiment;

(Continued)

From FIG. 1 to FIG. 4 to FIG. 5 in the second embodiment;
 From FIG. 6 to FIG. 7 to FIG. 8 in the third embodiment;
 From FIG. 6 to FIG. 9 to FIG. 10 in the fourth embodiment;
 From FIG. 11 to FIG. 12 to FIG. 13 in the fifth embodiment;
 From FIG. 11 to FIG. 14 to FIG. 15 in the sixth embodiment;
 From FIG. 16 to FIG. 17 to FIG. 18 in the seventh embodiment; and
 From FIG. 16 to FIG. 19 to FIG. 20 in the eighth embodiment.

The process or period in which an image transitions to another image forms no part of the claimed design.

The broken line showing a display screen, and all other broken lines showing portions of the graphical user interface illustrate portions of the article. None of the aforementioned broken line subject matter forms part of the claimed design.
